UNITED STATES PATENT OFFICE.

FLOYD N. PERKINS, OF FREEPORT, ILLINOIS, ASSIGNOR TO ARCADE MANUFACTURING COMPANY, OF FREEPORT, ILLINOIS, A CORPORATION OF ILLINOIS.

LATCH.

1,171,975.

Specification of Letters Patent. Patented Feb. 15, 1916.

Application filed December 29, 1913. Serial No. 809,152.

To all whom it may concern:

Be it known that I, FLOYD N. PERKINS, residing at Freeport, in the county of Stephenson and State of Illinois, have invented certain new and useful Improvements in Latches, of which the following is a specification.

My invention relates to certain improvements in latches of the class in which an arm swinging substantially in the plane of the door is pivoted upon a suitable base plate fastened upon either the door or the casing and arranged to swing over and upon a plate having an inclined surface secured 15 to the other of said parts.

The purpose of the invention is to provide simple means through which the closing of the door may operate to throw the swinging arm from the open to the locked 20 position.

To such end it consists in certain novel characteristics which will appear in connection with the description of the preferred form of the invention herein shown and described and the essential features of which will be clearly pointed out in the claims 25 appended hereto.

In the drawings, Figure 1 is a front elevation of a complete latch embodying my invention. Fig. 2 is a sectional view looking 30 at the plane 2-2 in the direction of the arrows. Fig. 3 is a view of a portion of Fig. 1, showing the locking arm in the upright or unlocked position. Fig. 4 is a section in the plane 4-4, looking in the direction of the arrows, and Fig. 5 is an under plan of 35 a plate adapted for attachment to the casing.

Referring to these drawings, A represents a part of a door and B, a part of the casing 40 against which it swings. Attached to the door is an incline, α^1 , continued downward in the form of a handle, α^1 , and laterally into a finger, α^2 . A plate, b, secured to the casing, has pivoted upon it a locking arm, 45 b^1 , turning upon a pivot, b^2 , Fig. 2, and swinging from a position upon the incline which is shown in Fig. 1, upward and toward the left into the position shown in

Fig. 3. The plate b has a stop, b^3 , Fig. 5, and the lower end of the pivot b^2 has fast 50 upon it a washer, b^6 , with a lug, b^7 , Fig. 5, arranged to engage the stop and check the movement of the locking arm when it reaches the position shown in Fig. 3. This position is slightly beyond the vertical line 55 of the pivot so that the weight of the arm holds it against the stop. A lug, b^5 , projects radially from the arm b^1 and bears a cam face, b^6 . When the arm is in the upper position shown in Fig. 3, the lug b^5 lies in 60 the path of the finger α^2 . When the door is closing the finger strikes the cam face b^5 and swings the arm b^1 toward the right, throwing it down upon the incline α .

I do not limit myself to the exact form 65 herein shown except as pointed out in the following claims, in which it is my intention to cover all of the patentable novelty in my invention over the prior art.

I claim as new and desire to secure by 70 Letters Patent—

1. A fastener of the character described, comprising a door pull handle having an incline adapted to form a rest and with a laterally projecting tongue, and a pivoted 75 lever provided with an inclined cam portion adapted in the closing of the door to engage the tongue and to cause said lever to swing across the meeting line of the door and its casing and to rest upon the incline of the 80 door pull handle, and thereby to lock said door, substantially as described.

2. A fastener of the character described, comprising a door pull handle having a projecting tongue and a pivoted lever provided 85 with a hub having as part an inclined cam adapted in the closing of the door to engage the tongue to operate said lever and thereby to lock said door, substantially as described.

3. In a device of the character described, 90 a door, a casing therefor, a lever pivotally mounted on the casing, said lever being adapted to project opposite the door, a cam attached to the door, an arm projecting therefrom beyond the edge of the door and 95 over the casing, and a cam attached to the

lever adjacent its pivot adapted to engage said arm on movement of the lever from opposite the door to partially open the door, said door also being tightly closed by engagement of the lever with the cam attached to the door.

In witness whereof I have signed the

above application for Letters Patent at Freeport, Illinois, this 3d day of December, A. D. 1913.

FLOYD N. PERKINS.
